UNITED STATES PATENT OFFICE.

THEODOR KUNDTZ, OF CLEVELAND, OHIO.

DESIGN FOR A SEWING-MACHINE CABINET.

SPECIFICATION forming part of Design No. 35,900, dated May 6, 1902.

Application filed April 11, 1902. Serial No. 102,483. Term of patent 7 years.

To all whom it may concern:

Be it known that I, THEODOR KUNDTZ, a citizen of the United States of America, residing at Cleveland, in the county of Cuyahoga and 5 State of Ohio, have invented and produced a new and original Design for Sewing-Machine Cabinets, of which the following is a specification, reference being had to the accompanying drawings, forming part thereof.

10 Figure I of the drawings is a view in perspective of a sewing-machine cabinet, showing my design. Fig. II is a front side elevation of the cabinet. Fig. I shows the forward side, the right-hand side, and the top of the 15 cabinet, but does not fully show the left-hand side, which is in every respect the same in design as the right-hand side and need not, therefore, be separately illustrated.

My design for a sewing-machine cabinet 20 comprises a horizontally-arranged top *a*, whose side edges are straight, as at *b*, at and along their central portion. The top *a* swells or curves outwardly, as at *c*, where the forward edge of the top joins the side edges of the 25 top. Two skeleton frames are arranged below and depend from opposite end portions, respectively, of the top *a*, and each of the said frames comprises two horizontally-arranged shelves *d*, arranged at different elevations, respectively, and upright bars *e*, connecting the said shelves together at the outer longitudinal edges of the shelves and extending to the top *a*, and vertically-arranged bars *f*, connecting the said shelves with the said 30 top at the inner extremities of the forward edges of the said shelves. Drawers *g* are arranged upon the shelves *d*. The outward swells or curves *c* of the forward edge of the top *a* extend from near the bars *f* to the adjacent bars *e*. The front of each drawer *g* 35 swells or curves outwardly, as at *h*, from near the adjacent bar *f* to the adjacent bar *e* and approximately conforms to the adjacent swell or curve *c* of the forward edge of the top *a*. The forward edge of each shelf *d* projects somewhat forwardly of the drawer upon the shelf and conforms to the outline of the

front of the said drawer. The forward edge of the top *a* adjacent to each bar *f* has a forwardly-facing rounded projection *k*, and 50 the outline of the said edge between the two projections *k* is a slight inward curve *l*. Next below the top *a*, between the two bars *f*, is a drawer *m*, which is arranged a short distance inwardly from the forward edge of the top. 55 The central portion of the front of the drawer *m* forms a slightly inwardly curved panel, and upon each end portion *n* of the said drawer next adjacent to the said panel appears an ornamental figure *o*, and each end portion *n* is enlarged downwardly toward the adjacent bar *f* and has a vertically-extending forwardly-rounded bulge *r* below the adjacent rounded projection *k* of the forward edge of the top *a*. Next below the central portion of 60 the drawer *m* is a panel *u*, which is arranged vertically and somewhat inwardly from the front of the drawer *m*, and at each end of the panel *u* is a vertically-arranged comparatively wide molding *x*, which extends from top to 65 bottom of the said panel *u* and has a face which curves sinuously transversely of the said molding, curving outwardly adjacent to the said panel and inwardly next to the adjacent bar *f*. It will be observed also that 70 the two moldings *x*, which are arranged at opposite ends, respectively, of the panel *u*, diverge forwardly from the said panel. Ornamental work *y* appears upon the central portion of the panel *u*. 75

The leading and characteristic and essential feature of my design comprises the unitary article, in its shape or configuration, as shown in the drawings.

What I claim is—

80 The design for a sewing-machine cabinet substantially as herein shown and described.

In testimony whereof I sign the foregoing specification, in the presence of two witnesses, this 3d day of April, 1902, at Cleveland, Ohio.

85 THEODOR KUNDTZ.

Witnesses:

C. H. DOVER,
TELSA SCHWARTZ.
